Term of patent 14 years

(Cl. D57—1)

FIG. 1

FIG. 2

FIG. 3

FIG. 4

FIG. 5

Figure 1 is a front elevational view of a pair of safety goggles embodying my new design;

Figure 2 is a top plan view thereof;

Figure 3 is a rear elevational view thereof;

Figure 4 is a side elevational view thereof as viewed from the right side in Figure 1; and

Figure 5 is a vertical sectional view taken substantially along the plane of line 5—5 in Figure 3.

The dominant features of my design reside in those portions shown in full lines.

I claim:

The ornamental design for a pair of safety goggles, substantially as shown and described.
